Attorney

UNITED STATES PATENT OFFICE

EMMA NICKUM, OF PHILADELPHIA, PENNSYLVANIA.

SANITARY CUSPIDOR.

1,001,216.

Specification of Letters Patent. Patented Aug. 22, 1911.

Application filed November 4, 1910. Serial No. 590,638.

To all whom it may concern:

Be it known that I, EMMA NICKUM, a citizen of the United States, residing at Philadelphia, in the county of Philadelphia and State of Pennsylvania, have invented 5 certain new and useful Improvements in Sanitary Cuspidors, of which the following is a specification.

My invention relates to improvements in 10 sanitary cuspidors, and more particularly to an improved removable receptacle for cuspidors, the object of the invention being to provide a water tight receptacle of paper, papier-mâché or any other suitable combustible material which may be positioned inside of an ordinary cuspidor, and catch and hold the matter deposited in the cuspidor, and which at the desired time may be closed 15 and sealed by a cover, readily removed 20 from the cuspidor without soiling the hands, and carried away and burned.

A primary object of the invention is to 25 provide an improved cuspidor or receptacle for a cuspidor, which is designed as a prevention against the spread of tuberculosis by reason of expectoration in public places. Ordinary cuspidors, which are more or less 30 imperfectly cleaned, do not remove the tubercular germ from the cuspidor, and it is a well known fact that the only positive 35 way of destroying such germs is to burn them. My device enables this to be done, and at the same time utilizes the ordinary cuspidors in use.

With these and other objects in view, the 40 invention consists in certain novel features of construction, and combinations and arrangements of parts, as will be more fully hereinafter described and pointed out in the claims.

In the accompanying drawings: Figure 1, is a view in vertical section illustrating 45 my improvements in position in a cuspidor. Fig. 2, is a perspective view of the receptacle removed. Fig. 3, is a perspective view of the cover for the receptacle shown in Fig. 2, and Fig. 4, is a view in vertical section through the receptacle showing the cover in place.

1, represents a cuspidor of the ordinary 50 type found in public places, having a removable conical cover 2, the latter provided at its lowest central point with an opening 3 through which the deposit on the cover 55 passes into the body 1. This invention is in no wise limited to the particular cuspi-

dor, the one shown being used for purposes of illustration only.

4, represents my improved receptacle which is preferably, though not essentially, of cylindrical form open at the top and having a closed bottom 5. This receptacle may be made of various materials such for example as papier-mâché or other material which is readily combustible, and 60 may be strengthened by reinforcing wires 6 and 7 preferably embedded in the material of the receptacle. Upwardly projecting handles or finger holds 8 are provided at opposite sides of the receptacle, and are 65 preferably of the general hook shape shown, the hooks projecting in opposite directions and strengthened by the reinforcing wires 7. By projecting these hook shaped finger holds or handles in opposite directions, the 70 person removing the receptacle from the cuspidor may readily project the fingers under the finger holds, and lift the receptacle out of the cuspidor without soiling the 75 hands.

When the receptacle is ready for carrying 80 away, it is closed and sealed tight by means of a cover 9 shown most clearly in Figs. 3 and 4. This cover is preferably of the same material as the receptacle, and is provided with a circular depending flange 10 adapted to inclose the upper edge of the receptacle 4, and provided on its inner face with mucilage or glue, which when moistened and the cover placed on the receptacle will adhere to the receptacle and effectually close 85 the same so that the device may be readily carried away and burned without danger of spilling any of the contents.

When the receptacle is provided with the 90 finger holds or handles 8, as shown in Fig. 2, it is necessary to provide notches 11 in the opposite edges of the cover to accommodate such handles or finger holds, and in positioning the cover, the finger holds are bent 95 outward far enough to allow the cover to move down over the receptacle.

These receptacles are designed to be placed in cuspidors in public places, and will be hid by the cover as shown in Fig. 1, so that 100 the cuspidor has its ordinary appearance. However all matter deposited on the cover will move into the receptacle, and not into contact with the body of the cuspidor, and when the receptacle is full, an attendant removes the cover, seals the receptacle by 105 means of the cover 9, and carries the full 110

receptacle away, leaving a clean and fresh receptacle in the cuspidor. After the receptacle is sealed and carried away, it is burned so that there can be no escape of any 5 tubercular or other germs which may be in the receptacle.

Various slight changes might be made in the general form and arrangement of parts described without departing from my invention, and hence I do not limit myself to the 10 precise details set forth, but consider myself at liberty to make such changes and alterations as fairly fall within the spirit and scope of the appended claims.

15 Having thus described my invention, what I claim as new and desire to secure by Letters Patent is:

1. A refuse receptacle of the character described, comprising a body and a cover normally off the body, integral upwardly projecting handles on said body, said cover having recesses to receive said handle and constructed to be secured by adhesive material to inclose the contents of said body, 20 substantially as described.

2. A refuse receptacle of the character described, comprising a body, and a cover, integral upwardly projecting handles on said body, all of said parts composed of combustible material, said cover having notches 25

30

to receive said handles, and said cover containing adhesive material to secure the cover onto the body, substantially as described.

3. A refuse receptacle of the character described, comprising a body and a cover normally off the body, integral upwardly projecting handles on said body, said cover having recesses to receive said handles and constructed to be secured by adhesive material to inclose the contents of said body, 35 the upper ends of said handles curved downwardly and in opposite directions, substantially as described.

4. A refuse receptacle of the character described, comprising a body, and a cover, integral upwardly projecting handles on said body, all of said parts composed of combustible material, said cover having notches to receive said handles, and said cover containing adhesive material to secure the cover 40 onto the body, the upper ends of said handles curved downwardly and in opposite directions, substantially as described.

In testimony whereof I have signed my name to this specification in the presence of 55 two subscribing witnesses.

EMMA. NICKUM.
